UNITED STATES PATENT OFFICE.

JOHN WHYTE, OF CHICAGO, ILLINOIS, ASSIGNOR, BY MESNE ASSIGNMENTS, TO THE SERVICE CLOTH PLEATING COMPANY, OF EVANSTON, ILLINOIS, A CORPORATION.

PLAITING-MACHINE.

1,399,231.

Specification of Letters Patent.

Patented Dec. 6, 1921.

Application filed December 13, 1920. Serial No. 430,337.

To all whom it may concern:

Be it known that I, JOHN WHYTE, a citizen of the United States, residing at Chicago, in the county of Cook and State of Illinois, have invented certain new and useful Improvements in Plaiting-Machines, of which the following is a specification.

One of the principal objects of my invention is to provide a machine in which a strip 10 of cloth may be steamed, plaited, pressed and deposited mechanically in a container. By its use many hand operations that are now necessary to steam, plait, press and deposit the cloth, are eliminated.

It is another object of my invention to provide plaiting fingers for accomplishing in a simple and efficient manner, the work of plaiting the cloth after it leaves the steaming means and before it reaches the pressing 20 device. My invention contemplates the mounting of these fingers on dogs carried by two endless sprocket chains, with stationary tracks between the latter to force the fingers into engagement with the cloth.

Other important and incidental objects will be brought out in the following specification, and particularly set forth in the subjoined claims.

In the accompanying drawings, Figure 30 1 is a side elevational view of my plaiting machine with one side frame and one set of operating fingers removed. Fig. 2 is an end view of said machine, showing the operating mechanism therefor. Fig. 3 is an enlarged view of a portion of the endless sprocket chains at the point where the plaiting fingers first engage the cloth. And Fig. 4 is a cross sectional view taken through one of the sprocket chains on the line $a-a$ 35 of Fig. 3, showing the plaiting finger mechanism.

Throughout the specification and drawings, similar reference characters denote corresponding parts.

Referring to the accompanying drawings, the numeral 1 designates a horizontal table upon one end of which there are secured bearings 2 for a transverse shaft 3 on which a driving pulley 4 is fast. Also secured to 50 the shaft 3 is a bevel gear 5 in mesh with a bevel gear 6 fast on the lower end of an inclined shaft 7 journaled in bearings 8, 9 and 10 secured, one above the other, to a top frame 11 supported by the table 1.

Fast on the shaft 7 above the bearing 9,

is a bevel gear 12 in mesh with a bevel gear 13 fast on a shaft 14 suitably journaled in the top frame 11. Secured to the shaft 14, one near each end thereof, are two sprocket wheels 15, one of which wheels is not shown. 60

Behind the latter on a transverse shaft 16 suitably journaled in the top frame 11, is a pair of sprocket wheels 17 one of which wheels is not shown. Around each sprocket wheel 15 and 17 passes an endless sprocket chain 18 65 which is turned when the sprocket wheels 15 are rotated by the means before described.

Suitably journaled in the top frame 11 above the transverse shaft 16, is a transverse shaft 19 on one end of which is fast a bevel gear 20 in mesh with a bevel gear 21 fast on the inclined shaft 7 above the bearing 10. Fast on the shaft 19, one near each end thereof, are two sprocket wheels 70 22 one of which wheels is not shown. In front of the latter there is suitably journaled in the top frame 11 above the shaft 14, a transverse shaft 23 on which there is secured a pair of sprocket wheels 24. Around 75 each sprocket wheel 22 and 24, there passes an endless sprocket chain 25 which is turned when the sprocket wheels 22 are rotated by the means hereinbefore described.

Rotatably supported by a bracket 26 projecting rearwardly from the top frame 11, is a roll 27 of cloth 28. This strip of cloth 28 passes forwardly between a steam chamber 28^a whose top portion is apertured, and a vacuum chamber 29 above the latter, 90 whose bottom portion is apertured, both of said chambers being secured to the rear end of the top frame 11. Steam is conducted to the chamber 28^a through a tube 30 for the purpose of steaming the cloth prior to 95 its being plaited by means to be hereinafter described. This steam is exhausted through the vacuum chamber 29 and communicating tube 31.

The cloth then passes between the lower 100 run of the sprocket chains 25 and the upper run of the sprocket chains 18, said chains carrying devices to be hereinafter described, for plaiting the cloth.

After the cloth passes between the endless 105 sprocket chains 18 and 25, it travels over a semi-circular guide 32 supported by the top frame 11, for the reception between two endless belts 33 and 34, preferably constructed of canvas, that pass over said 110

guide. Suitably mounted in the frame 11, at the top end of the guide 32, is an upper roller 35 and a lower roller 36. The upper canvas belt 33 after passing around a drive 5 pulley 37 fast on the drive shaft 3, travels around guide rollers 38 and 39, then around the roller 35 and over the guide 32, and then around a roller 40 supported on the rear end of the table 1, to the drive pulley 37. 10 The lower canvas belt 34 after passing around the lower roller 36 and over the guide 32, travels around a roller 41 supported by the rear end of the top frame 11, and then around guide rollers 42 and 43 15 to the lower roller 36. (See Fig. 1.)

The cloth 28 is presented by the canvas belts 33 and 34 to the pressing means now to be described. Mounted upon the table 1 is a pressing weight 44 to which are secured 20 rods 45 which project downwardly through guides 46 in the table 1. Surrounding the lower end of each rod 45, between the lower end of the guide 46 and a washer 47 on the rod, is a coil spring 48 which is compressed 25 by a nut 49 on the lower threaded end of the rod to draw the pressing weight 44 into sufficiently tight engagement with the cloth to press it. By turning the nuts 49 on the lower threaded ends of the rods 45, it is 30 easily possible to adjust the tension of the springs 48 to secure the desired pressure of the pressing weight upon the cloth.

After passing under the pressing weight 44, the cloth 28 travels over a roll 50 carried by the lower ends of oscillatory levers 51, one of which levers is not shown. These levers 51 are pivotally secured at their upper ends within the top frame 11. Each lever 51 is oscillated by an eccentric rod 53 connected 40 to an eccentric 54 on the shaft 16. The oscillatory mechanism just described delivers the cloth, in a wave like manner, to a container 55 below. (See Fig. 1.)

The means employed for plaiting the cloth 45 as it passes between the sprocket chains, will now be described. Secured to each adjacent pair of pins 56 in the sprocket chain 18, is a pair of dogs 57. Each dog 57 has a downwardly projecting lug portion 58 50 through which there loosely projects a horizontal bolt 59. The head of this bolt restrains the outward movement of the lug portion 58 of one dog 57, while a nut 60 on the other end of the bolt limits the outward 55 movement of the lug portion of the companion dog 57. Encircling the bolt 59 between these adjacent lug portions 58 on the respective dogs, is a coil spring 61, which is compressed when these lug portions are moved 60 toward each other by the means now to be described.

Each dog 57 of a coöperating pair, has an upwardly pointing horn-shaped portion 62. To the outer ends of these horn shaped portions, which cross each other in scissors fash-

ion, there are secured bowed plaiting fingers 63 which also cross each other in scissors fashion. Supported by the top frame 11 below the upper run of each sprocket chain 18, is a track 64 having inclined ends that project approximately to the vertical axes of the sprocket wheels 15 and 17. The rear inclined end of each track 64 is in the path of forward movement of the horn-shaped portions 62 of the dogs 57 as the latter are carried upwardly by the sprocket chains 18, with the result that when said horn portions of the dogs engage the inclined ends of the tracks, they will be elevated by it to press the plaiting fingers 63 upwardly and outwardly into engagement with the cloth 28, as shown in Fig. 3.

Similar, but inverted, plaiting fingers 65 are secured to inverted horn-shaped portions 66 of inverted dogs 67 carried by each 85 sprocket chain 25. When the horn-shaped portions 66 of the dogs 67 engage the inclined ends of a track 68 above the lower run of the sprocket chain 25, they will force the lower ends of the plaiting fingers 65 which they carry, into a gradually expanding downward engagement with the cloth 28, between each pair of upwardly expanding fingers 63, to give said cloth a box plait.

When the horn-shaped portions 62 of the 95 dogs 57 start to travel down the inclined front ends of the tracks 64, the pressure of the compressed springs 61 will press the lug portions 58 of said dogs outwardly to draw the plaiting fingers 63 downwardly from engagement with the cloth 28, just prior to its entrance between the canvas belts 33 and 34. Similarly, when the horn-shaped portions 66 of the inverted dogs 67 come to the front inclined ends of the tracks 68, the pressure of 100 compressed springs 69, similar to springs 61, will press lug portions 70 on said dogs 67 outwardly along bolts 71 to draw the plaiting fingers 65 upwardly out of engagement with the cloth.

It will be observed from Figs. 3 and 4, that I have placed one set of dogs on one side, and the next succeeding set of dogs on the opposite side, of each sprocket chain. This permits two dogs to be mounted on each 115 sprocket pin, one on each side of the sprocket chain, so that the horn shaped portion of one dog will point in one direction and the horn-shaped portion of the dog on the other side of the sprocket chain will point in the opposite direction. There are also two tracks for each sprocket chain, one on each side thereof to be engaged by the horn-shaped portions of the dogs. It is thus possible by placing the dogs and a track on 120 each side of a sprocket chain, to provide a pair of plaiting fingers in the space between each two pins in said chain.

The machine is controlled by a hand lever 72 fast on a shaft 73 on which is secured a 130

rocker arm 74 that operates a clutch 75 which secures the pulley 4 in and out of driving engagement with the shaft 3.

After the plaiting fingers are withdrawn 5 from engagement with the cloth, it is received by the canvas belts 33 and 34 for presentation to the pressing weight 44, by which it is thoroughly pressed, and there-after deposited in the container 55. It is 10 thus seen that the cloth is not only steamed, plaited and pressed without hand operations, but that it is deposited mechanically in the container.

Having described my invention, I claim: 15 1. In a machine of the type described, the combination with a table, of a steaming device at one end of said table, through which a strip of cloth is adapted to pass, pressing means also supported by said table, a pair of 20 superimposed endless elements, and means carried by said elements for plaiting said cloth after it leaves the steaming means and before it reaches the pressing means.

2. In a machine of the type described, the 25 combination with a table, of a pair of superimposed endless elements supported above said table, a cloth passing between the lower run of the upper endless element and the upper run of the lower endless element, plaiting fingers carried by said endless elements, and stationary means for forcing said fingers outwardly into engagement with the cloth as it passes between said endless elements, for the purpose specified.

3. In a machine of the type described, the 35 combination with a table, of a pair of superimposed sprocket chains supported for movement together above said table, a cloth passing between the lower run of the upper sprocket chain and the upper run of the lower sprocket chain, dogs pivotally secured to said sprocket chains, plaiting fingers carried by said dogs, and stationary means between the sprocket chains for forcing said 40 fingers outwardly into engagement with the cloth, for the purpose specified.

4. In a machine of the type described, the 45 combination with a table, of a pair of superimposed sprocket chains supported for movement together above said table, a cloth passing between the lower run of the upper sprocket chain and the upper run of the lower sprocket chain, plaiting fingers carried by said sprocket chains, stationary means for forcing said fingers outwardly into engagement with the cloth, and spring means for returning said fingers to their 50 normal positions after they have passed the stationary means.

5. In a machine of the type described, the 55 combination with a table, of a pair of superimposed sprocket chains supported for movement together above said table, a cloth passing between the lower run of the upper sprocket chain and the upper run of the 60 lower sprocket chain, dogs pivotally secured to said sprocket chains, plaiting fingers carried by said dogs, stationary means between the sprocket chains for forcing said fingers outwardly into engagement with the cloth, and a spring 65 between each two dogs adapted to be compressed when the plaiting fingers are moved outwardly by the stationary means, to return said fingers to their normal positions after they have passed the stationary means.

lower sprocket chain, dogs pivotally secured to said sprocket chains, plaiting fingers carried by said dogs, stationary means between the sprocket chains for forcing said fingers outwardly into engagement with the cloth, 70 lugs on said dogs, and a spring between each two lugs adapted to be compressed when the plaiting fingers are moved outwardly by the stationary means, to return said fingers to their normal positions after they have passed the stationary means.

6. In a machine of the type described, the combination with a table, of a pair of superimposed sprocket chains supported for movement together above said table, a cloth passing between the lower run of the upper sprocket chain and the upper run of the lower sprocket chain, dogs pivotally secured to said sprocket chains, a horn-shaped portion on each dog adapted to cross in scissors fashion the horn-shaped portion of the adjacent dog, plaiting fingers adapted to cross each other in scissors fashion, secured to the coöperating horn-shaped portions of each pair of dogs, and a stationary track 80 adapted to be engaged by the said horn-shaped portions of the dogs, to move the free ends of the plaiting fingers outwardly into engagement with the cloth, for the purpose specified.

7. In a machine of the type described, the combination with a table, of a pair of superimposed sprocket chains supported for movement together above said table, a cloth passing between the lower run of the upper sprocket chain and the upper run of the lower sprocket chain, dogs pivotally secured to said sprocket chains, a horn-shaped portion on each dog adapted to cross in scissors fashion the horn-shaped portion of the adjacent dog, plaiting fingers adapted to cross each other in scissors fashion, secured to the coöperating horn-shaped portions of each pair of dogs, a stationary track, with inclined ends, adapted to be engaged by said 100 horn-shaped portions of the dogs, to move the free ends of the plaiting fingers outwardly into engagement with the cloth, a lug on each dog, projecting in a direction opposite to that of its horn-shaped portion, a horizontal rod projecting loosely through the free ends of the lugs of each coöperating pair of dogs, and a spring surrounding said rod between the lugs, adapted to be compressed when the plaiting fingers are moved 105 outwardly by the track, to return said fingers to their normal positions after they have passed said track.

8. In a machine of the type described, the combination with a table, of a pair of superimposed sprocket chains supported for movement together above said table, a cloth passing between the lower run of the upper sprocket chain and the upper run of the lower sprocket chain, a series of pairs of 110

5 plaiting fingers that cross each other in scissors fashion, secured to each sprocket chain, the fingers on the upper chain being alternately disposed with those of the lower chain, and stationary means for forcing the plaiting fingers of each upper and lower pair, outwardly into alternate engagement with the cloth, for the purpose specified.

9. In a machine of the type described, the 10 combination with a table, of a steaming device at one end of said table, through which a strip of cloth is adapted to pass, means supported by said table for plaiting said cloth after it has been steamed, pressing means in 15 said table for pressing the cloth after it has been steamed, and oscillating means for de-

positing said cloth in a wavelike manner in a container after it has been pressed.

10. In a machine of the type described, the combination with a table, means supported by said table for plaiting a strip of cloth, pressing means in said table, a semi-circular guide between the plaiting and pressing means, and a pair of endless canvas belts movable over said semi-circular 20 guide to receive said cloth from the plaiting means and present it to the pressing means.

In testimony whereof I have hereunto set my hand this 11th day of December, 1920.

JOHN WHYTE.

Witness:

HOWARD S. SMITH.
